United States Patent Office

Des. 207,786
Patented May 30, 1967

207,786

CUP OR SIMILAR ARTICLE

Frank J. Benes, Lancaster, Ohio, assignor to Anchor Hocking Glass Corporation, Lancaster, Ohio, a corporation of Delaware

Filed Jan. 5, 1966, Ser. No. 468

Term of patent 14 years

(Cl. D44—9)

Fig. 1.

Fig. 2.

Fig. 3.

FIG. 4.

FIG. 5.

FIG. 6.

FIG. 7.

FIG. 1 is a side elevational view of a cup or similar article showing my new design;

FIG. 2 is a top plan view of the cup shown in FIG. 1;

FIG. 3 is a rear elevational view of the cup shown in FIG. 1;

FIG. 4 is a side elevational view of a cup or similar article showing another form of my new design wherein the upper edge opposite the handle is provided with a pouring lip;

FIG. 5 is a front elevational view thereof;

FIG. 6 is a rear elevational view thereof; and

FIG. 7 is a top elevational view thereof.

I claim:

The ornamental design for a cup or similar article, substantially as shown.
